UNITED STATES PATENT OFFICE.

LOUIS J. PERKINS, OF LEWISTON, IDAHO

EXPLOSIVE-ENGINE-PRIMING MECHANISM.

1,088,792.

Specification of Letters Patent.

Patented Mar. 3, 1914.

Application filed May 20, 1913. Serial No. 768,827.

To all whom it may concern:

Be it known that I, LOUIS J. PERKINS, a citizen of the United States, residing at Lewiston, in the county of Nez Perce and State of Idaho, have invented a new and useful Explosive-Engine-Priming Mechanism, of which the following is a specification.

The present invention relates to improvements in an explosive engine priming mechanism, one object of the invention being the provision of means for atomizing a carbureted air into the cylinders of an explosive engine, the fuel for atomization being brought from the carbureter float chamber and atomized either through the instrumentality of air under pressure or through an atomizing bulb or pump, there being provided manually controlled valves, one for each cylinder, for operation to connect the atomizing pipe for communication with the cylinder.

A further object of the present invention is the provision of manually controlled means for operating the valves to the atomizing device and to either the compressed supply or atomizing bulb or pump.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a side elevation of an explosion engine equipped with the present invention. Fig. 2 is an end elevation showing the method of connecting the atomizer to the carbureter. Figs. 3, 4, 5 and 6 are detail views of the various parts of the priming mechanism.

Referring to the drawings, the numeral 1 designates the explosion motor or engine, which in the present instance is shown as a four-cylinder type, two cylinders of which are cast *en bloc*, each one being provided with either the nipple 2 or the nipple 2' disposed in the head thereof and in position to inject the priming charge into the explosion chamber of the motor.

A valve 3 is carried by each of the nipples, and as the nipple 2 is provided with the single introduction port 4, the valve 3 is pro-

vided with a single introduction port 5. The nipple 2', which as before stated is interchangeable with the nipple 2 is provided with the three ports 4' and 4'', which are disposed at the proper time to be placed in registration with the three ports 5' and 5'' of the valve 3', so that when the priming charge is admitted through the ports 5'-4', any air pressure within the cylinder will be exhausted through the ports 4''-5'', all as clearly illustrated in Fig. 5. In order to operate all of the respective valves 3 or 3', each is provided with a handle 5'' which is operably connected to the slidable rod 6 provided with a handle 7, said rod being projected through the dash-board 8 so as to be in ready access to the chauffeur.

Led to each one of the nipples 2-2' and connected to the reduced portions 9 thereof, are the flexible conduits or tubes 10, one to each cylinder, the opposite end of said tubes being connected in the dome 11 of the atomizing chamber 12. This chamber 12 is supported from the float chamber 13 of the carbureter. A tube 14 is disposed in the wall of the carbureter and has its inlet end 15 projected into the fuel within the float chamber 13 while its nozzle end 16 is projected concentrically of the atomizing chamber 12 and in line to receive a stream of air from the air induction nozzle 17 of the pipe 18.

In order to provide for the proper introduction of air through the conduit 18, the compressed air tank 19 is provided, a pipe 20 being led therefrom and through the valve casing 21 to the conduit 18. The valve casing 21, as clearly illustrated in Fig. 6, is provided with the valve 22 having the two ports 22' for registration with the conduits 20 and 18, and with the conduits 23 and 18, said conduit 23 being extended through the dash-board 8 and provided with the manually controlled air supplying means 24, which may be either a hand pump or a bulb.

In order to operate the valve 22, a handle 25 is connected thereto, a rod 26 being connected to the handle and extended through the dash board 8 adjacent the air supplying means 24, the knob 27 being mounted upon the outer end of the rod to permit of the ready manipulation thereof. By means of the rod 26, the valve 22 may be operated to select either the air from the tank 19 or the air supplied by the device 24. Mounted in the atomizing pipe 14 is a valve 28, whose

handle 29 is operably connected to the rod 30, said rod being normally held to close the valve by means of the spring 31. In order that the valve 28 may be operated 5 coincident with the valves 3-3' when the rod 6 is pulled upon, a lever 32 is pivoted to the dash board as at 33 and has its upper end disposed to be engaged by the pin 34 upon the rod 6, and its lower end operably 10 connected at 35 to the rod 30. It will thus be seen that when the rod 6 is pulled upon, the upper end of the lever 32 will be moved toward the dash board 8, while the lower end will cause the rod 30 to be pushed out 15 wardly and thus operate the handle 29 to open the valve 28.

From the foregoing description, it is evident that by connecting the atomizing nozzle 14 directly with the carbureter, that the fuel 20 is always at hand to be properly atomized through the nozzle end 16 thereof and into the dome 11 of the atomizing casing 12, from where it is distributed through the conduits 10 to the various valved nipples connected 25 to the cylinders of the engine. By this means instead of injecting into the cylinders, the liquid fuel directly, the effect of the air upon the atomized fuel will produce the desired carbureted air, which when introduced into the cylinders, will be more 30 readily exploded, when the ignition system is actuated as is the usual custom to produce the spark within the cylinders.

It is evident that an apparatus installed 35 and arranged as the present one, the liquid is readily atomized within the cylinders, and that the usual cranking of the explosion engine is overcome, as it is simply necessary to operate the rods 6 and 26, when air pressure 40 is within the tank 19, to cause the proper atomization of the carbureted air into the respective cylinders. If desired when the air pressure has been decreased sufficiently to render the atomization 45 insufficient, the valve 36 may be closed and the pump 24 operated to produce the necessary air pressure for atomization, or the hand pump 24 may be used entirely.

What is claimed is:

50 1. The combination with an explosive en-

gine, and the fuel chamber of a carbureter, of an atomizing priming mechanism connected to supply carbureted air from the chamber of the carbureter to the cylinder of the engine, said mechanism including a conduit provided with a nozzle and led from the fuel chamber of the carbureter, an atomizing and air receiving chamber surrounding the nozzle, a conduit led from the chamber to the cylinder of the engine, an air supplying conduit led into the atomizing chamber in atomizing relation to the fuel nozzle, a manually opened valve mounted in the conduit leading to the cylinder, a manually controlled valve in the air supplying conduit, an air pressure tank in communication with the air supply conduit, and a manually controlled pumping device operably connected to the air supplying conduit, the air controlling valve being disposed selectively for connecting the tank or the manually controlled air supplying device to the air conduit.

2. A priming mechanism for explosive engines, including the float chamber of a carbureter, a conduit having a nozzle in communication with the float chamber, an air receiving and atomizing chamber surrounding the nozzle thereof, a valve in said conduit, a conduit led from the atomizing chamber to the cylinder of an explosion engine, a valve in said conduit, an air supplying conduit led to the atomizing chamber, means for operating coincidently the valve of the atomizing conduit and the valve of the conduit led to the cylinder, an air pressure supply connected to the air supplying conduit, a manually controlled supplying device connected to said conduit, and a manually controlled valve for selectively connecting the air supply pressure device or the manually operated air supplying device to the conduit.

In testimony that I claim the foregoing as my own, I have hereto affixed my signature in the presence of two witnesses.

LOUIS J. PERKINS.
